UNITED STATES PATENT OFFICE.

JOSEPH ANTONIUS FREDERIK GRIMBEL DU BOIS, OF AMSTERDAM, HOLLAND.

PAPER HOLDER.

1,413,975.

Specification of Letters Patent. Patented Apr. 25, 1922.

Application filed June 27, 1921. Serial No. 480,675.

To all whom it may concern:

Be it known that I, JOSEPH A. F. GRIMBEL DU BOS, a citizen of Holland, and a resident of Amsterdam, Holland, have made certain new and useful Improvements in Paper Holders, of which the following is a specification.

The present invention relates to paper holders, and more particularly to paper holders of the type especially adapted to retain sheets of paper in desired position.

An important object of the invention is to provide a paper holder of this character which will be effective to retain a letter, check, bill, or sheet of paper of any kind in position for convenient observation or in certain position when in process of assortment, irrespective of the influences of air currents or other forces tending to displace the sheets from proper position.

Another important object is to provide a paper holder of this character which is automatic in operation, requiring only a single movement of one hand of the operator to place the sheet in proper position under the control of the paper holder.

Other objects and advantages reside in the certain novel features of the construction, arrangement and combination of parts which will become apparent as the description proceeds, reference being had to the accompanying drawings forming part of this specification, and in which:—

Figure 1 is a side elevational view of my invention with the parts in normal position, a sheet being about to be placed in the paper holder;

Figure 2 is a sectional view taken on line 2—2 of Figure 1 looking in the direction of the arrows;

Figure 3 is a plan view of the grippers and associated structure;

Figure 4 is a sectional view on line 4—4 of Figure 1, looking in the direction of the arrows;

Figure 5 is a sectional view on line 5—5 of Figure 1, looking in the direction of the arrows;

Figure 6 is a side elevational view showing the parts in position assumed immediately before the sheet is in proper position on the table;

Figure 7 is a side elevational view showing the parts in position assumed immediately after the sheet is properly positioned on the table.

Referring to the drawings it will be seen the invention contemplates a support indicated generally at 10, which consists of a bed 11 mounted upon legs 12. The bed 11 is provided with an extension 13 and with a bearing 14 for a purpose to be hereinafter more fully described.

The bearing 14 depends vertically from the bed 11 and is of hollow cylindrical structure having a vertical slot 15 at one side thereof, as shown in Figure 2.

A table 16 adapted to receive the sheets is disposed above the bed 11 and spaced therefrom. Vertically depending from the table 16 is a supporting rod 17 which is slidably journaled in the bearing 14 of the bed. A coil spring 20 is mounted on the supporting rod 17 having its lower end bearing against the table, and its upper end bearing against a collar 21 secured upon the upper end of the supporting rod 17 by the set screw 22. The lower end of the supporting rod 17 has integrally formed therewith an outwardly and upwardly extending arm 23 having an outer inclined surface 24 constituting a cam, as will be hereinafter more fully described. The cam passes through a slot in the bed 11 and prevents rotary motion of the table 16. A stop 25 is secured to the upper side of the bed 11 and serves to limit the movement of the table 16 toward the bed 11 while the upward movement of the table 16 is limited by means of a screw 18.

Curved gripper arms 26 have their lower ends depending vertically as shown at 27 and fulcrumed at 28 to the bed extension 13. The upper outer ends of the gripper arms terminate in bearings 29 which receive the shaft 30 upon which the grippers 31 are journaled. The grippers 31 comprise body portions of heavy metallic structure, and preferably are provided with a suitable groove therein to receive cushioning elements preferably in the form of rubber tires 31'. The shaft 30 fits loosely in the bearings 29 so as to permit rotary movement of the grippers. As shown especially in Figure 3, there is a pair of curved gripper arms 26 which are spaced from each other and preferably are connected by an integral web 32.

Means are provided for resiliently maintaining the grippers 31 normally bearing against the table 16 and for returning the grippers to this position. This means includes a retractile spring 33 having one end secured to the bracket 34 depending from

the underside of the bed 11 and its other end secured to the cross pin 35 fastened to the vertically depending portions 27 of the curved gripper arms.

5 A push rod 36 is disposed beneath the bed 11 and serves to transmit motion from the cam 23 to the gripper arms to actuate the same through the desired movements. On the end of the push rod adjacent the cam a 10 yoke 37 is secured, and is provided at its outer end with eyes in which the shaft 38 is journaled. A follower 39 is loosely mounted on the shaft centrally thereof and guide rollers 40 are loosely mounted adjacent each 15 end of the shaft. The guide rollers 40 of the shaft 38 operate in channel guides 41, which are suspended by suitable brackets 42 from the lower side of the bed.

The push rod 36 extends through a suitable opening provided in the bracket 34 and adjacent the bracket 34 a hanger 43 depends upon the underside of the bed 11 between the rollers 44 of which, the push rod 36 is mounted. It is obvious that the portion of the push 20 rod between the channel guides 41 and the hanger 43 is constrained to rectilinear motion. The end of the push rod remote from the cam is mounted for vertical swinging motion as well as for rectilinear motion by 25 virtue of the joint 45. This swinging section of the push rod is normally held for rectilinear motion by guide roller 46 engaging the underside thereof, and a blade spring 47 engaging the upper side thereof.

30 The follower of the push rod is maintained at all times in engagement with the cam 23 by a coil spring 48 mounted on the push rod and having one end bearing against the bracket 34 and the other end bearing against 35 a collar 49 secured to the push rod, as shown 40 in the drawings.

The outer end of the push rod is provided with a roller 50 which bears against the abutment block 51 loosely mounted upon the 45 shaft 52 extending between the lower ends of the curved gripper arms 26. The outer end of the block 51 is loosely mounted upon a shaft 53 parallel to the shaft 52 and supported in a parallel link 54 having its lower 50 end pivoted at 55 also parallel to the shaft 28.

A sheet indicating a letter, check, bill or the like is indicated at 56.

In operation when it is desired to place the sheet upon the table it is laid thereon in the 55 position shown in Figure 1, with the upper end or head of the sheet lying upon the top of the grippers and gripping arms. In placing the sheet the operator exerts a pressure upon the table and depresses the same 60 against the action of the spring 20, as shown in Figure 6. The depression of the table moves the cam 23 downwardly and the cam engaging a follower of the push rod in turn moves the push rod longitudinally. The 65 roller 50 of the push rod engaging the abut-

ment block 51 causes the curved arms 26 to swing about the fulcrum 28 against the action of spring 33. This swinging movement of the gripper arms moves the grippers upwardly and away from the table and the 70 sheet then drops by gravity to the table, as shown in Figure 6. When the sheet lies upon the table in proper position, the table 16 has been depressed to the full extent, the stop 25 preventing further depression. At this 75 time the abutment block 51 has been thrown about the shaft 28 and the shaft 55, by the action of the roller 50 of the push rod until the top edge of the block lies below the center of the roller 50. A component of the force 80 of the retractile spring 33 is then exerted to throw the swinging section of the push rod upwardly above the abutment block and the grippers are then thrown to position to engage the sheet by the retractile spring 33, 85 all of which occurs of course immediately as the table has been depressed to the full extent and does not depend upon the release of pressure by the operator. When the operator does release the table, the spring 20 at 90 once moves the same upwardly to normal position shown in Figure 1, carrying the cam 23 with it. The coil spring 48 then returns the push rod to the position shown in Figure 1.

95 In this manner a sheet or any number of sheets may be positioned for convenient observation or in desired place, and effectively retained in position, irrespective of the influence of air currents or other forces tending to displace them from proper position.

I claim:

1. In a paper holder of the character described, a support including a bed having a bearing therein, and a bed extension, a 105 deppressible table disposed above said bed and spaced therefrom, a vertically depending supporting rod carried by said table and slidably mounted in said bearing, a coil spring mounted on said supporting rod for 110 maintaining said table in normal position, grippers associated with said table and normally bearing thereagainst, curved gripper arms carrying said grippers having lower vertically depending arms fulcrumed 115 to said bed extension, a cam carried by said supporting rod and actuated by the depression of said table, means for transmitting motion from said cam to said gripping arms for moving said grippers away from said 120 table to permit a sheet to be placed thereon, including a push rod and a retractile spring having one end connected to the vertically depending arm of said curved gripping arms and the other end connected to the underside 125 of said table for returning said grippers to said table to retain said sheet in position thereon, all as and for the purposes set forth.

2. In a paper holder of the character described, a support, a deppressible table dis- 130

posed above said support and spaced therefrom, spring means for maintaining said table in normal position, grippers associated with said table and normally bearing there-
 5 against, curved gripper arms carrying said grippers, and each having a vertically depending arm fulcrumed to said support, an abutment block carried between said gripping arms, a cam actuated by the depression
 10 of said table, means for transmitting motion of said cam to said gripper arms including a push rod having a vertically swinging section, automatically disconnected from engagement with said abutment block when
 15 the sheet is in proper position on said table, and a retractile spring for returning said grippers to said table to retain said sheet in position thereon.

3. In a paper holder of the character de-
 20 scribed, a support, a depressible table dis-
 posed above said support and spaced there-
 from, spring means for maintaining said table in normal position, grippers associated with said table and normally bearing there-
 25 against, curved gripping arms carrying said grippers, and each having a vertically depending arm fulcrumed to said support, an abutment block carried between said gripping arms, a cam actuated by the depression
 30 of said table, and means for transmitting motion of said cam to said gripper arms including a push rod having a vertically swinging section, automatically disconnected from engagement with said abutment block
 35 when the sheet is in proper position on said table.

4. In a paper holder of the character de-
 40 scribed, a support, a depressible table dis-
 posed above said support and spaced there-
 from, spring means for maintaining said table in normal position, grippers associated with said table and normally bearing thereagainst, a cam actuated by the depression of said table, means for transmitting motion of said cam to said grippers includ-
 45 ing a push rod, and a spring for maintaining said push rod in engagement with such cam, and means for returning said grippers to said table to retain said sheet in position thereon, all as and for the purposes set forth.

5. In a paper holder of the character de-
 55 scribed, a support, a depressible table dis-
 posed above said support and spaced there-
 from, spring means for maintaining said table in normal position, grippers associated with said table and normally bearing thereagainst, a cam actuated by the depression of said table, means for transmitting motion of said cam to said grippers including a push rod, and means for returning said grippers to said table to retain said sheet in position thereon, all as and for the purposes set forth.

65 6. In a paper holder of the character de-

scribed, a support, a depressible table dis-
 posed above said support and spaced there-
 from, spring means for maintaining said table in normal position, grippers associated with said table and normally bearing there-
 70 against, a cam actuated by the depression of said table for moving said grippers away from said table to permit a sheet to be placed thereon, and means for returning said grippers to said table to retain said sheet in posi-
 75 tion thereon, all as and for the purposes set forth.

7. In a paper holder of the character de-
 scribed, a support, a depressible table dis-
 posed above said support and spaced there-
 from, spring means for maintaining said table in normal position, grippers associated with said table and normally bearing there-
 80 against, a cam actuated by the depression of said table, means for transmitting motion from said cam to said grippers to move the same away from said table to permit a sheet to be placed thereon, and means for re-
 85 turning said grippers to said table to retain said sheet in position thereon, all as and for the purposes set forth.

8. In a paper holder of the character de-
 scribed, a support, a depressible table dis-
 posed above said support and spaced there-
 from, spring means for maintaining said table in normal position, grippers associated with said table and normally bearing there-
 90 against, a cam actuated by the depression of said table, means for transmitting motion from said cam to said grippers to 95 move the same away from said table to per-
 mit a sheet to be placed thereon, and auto-
 matically disconnected when said sheet is in position thereon, and means for returning said grippers to said table to retain said sheet in position thereon, all as and for the purposes set forth.

9. In a paper holder of the character de-
 scribed, a support, a depressible table dis-
 posed above said support and spaced there-
 from, spring means for maintaining the table in normal position, grippers associated with said table and normally bearing there-
 100 against, curved gripper arms carrying said grippers and each having a vertical depend-
 105 ing arm fulcrumed to said support, an abut-
 ment block carried between said gripper arms, a cam actuated by the depression of said table, means for transmitting motion of said cam to said gripper arms including a push rod hav-
 110 ing a vertically swinging section engageable with the abutment block, and a blade spring carried by the support and engageable with the vertically swinging section whereby the push rod is automatically disengaged from
 115 the abutment block when the sheet is in proper position on said table, and means for returning said grippers to said table to retain said sheet in position thereon.
